Sam'l. M. Gibbs Albany N.Y. (less to Augustus Quackenbush)
Letters Patent (Design No 84.) dated 3rd October 1816

The schedule referred to in these Letters Patent and making part
of the same

To all whom it may concern

I doth declare that

I, Samuel M. Gibbs of Albany in the County of Albany and State
of New York have invented or produced a new and useful ornamental
Design for an air tight Cooking Stove, and I do hereby declare that the
accompanying drawing is a full and accurate representation of a stove
constructed after my said design, exhibiting clearly the form and
arrangement of ornamental figures thereon.

What I claim as my invention and desire to secure by letters
Patent is the combination and arrangement of ornamental figures
represented in the accompanying drawings forming an ornamental
design for an air tight Cooking Stove.
